(57) **CLAIM**

The ornamental design for a connector assembly, as shown and described.

DESCRIPTION

FIG. 1 is a front, right, top perspective view of a connector assembly, showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front, left, bottom perspective view thereof;

FIG. 9 is a front, right, bottom perspective view thereof;

FIG. 10 is a rear, left, bottom perspective view thereof;

FIG. 11 is another front, right, top perspective view of the connector assembly;

FIG. 12 is a cross sectional view of the connector assembly of FIG. 12; and,

FIG. 13 is another cross sectional view of the connector assembly of FIG. 12.

The broken lines shown in the Figures are included to show unclaimed subject matter only and form no part of the claimed design.

1 Claim, 8 Drawing Sheets
